UNITED STATES PATENT OFFICE.

ROBERT J. DYER, OF OAKLAND, CALIFORNIA.

KILN.

Application filed July 11, 1921. Serial No. 483,735.

To all whom it may concern:

Be it known that I, ROBERT J. DYER, a citizen of the United States, residing at the city of Oakland, in the county of Alameda 5 and State of California, have invented certain new and useful Improvements in Kilns, of which the following is a specification.

This invention relates to an improvement in kilns, and more particularly to that type 10 commonly known as a "biscuit" kiln.

The invention has for its principal object to provide an arrangement of kilns whereby the heat from one kiln is capable of being transferred to another kiln prior 15 to discharging through the stack, whereby one kiln may be dried by the heat of another kiln being fired, or may be additionally heated by the heat from another kiln.

The invention consists primarily in a plurality of successively communicating kilns 20 discharging into a common stack, and containing a damper arrangement adapted for operation to control the direction of flow of the heat as it leaves the kiln.

With the above mentioned and other objects in view, the invention consists in the novel construction and combination of parts hereinafter described, illustrated in the accompanying drawings, and set forth in the 25 claim hereto appended, it being understood that various changes in the form, proportion, size and minor details of construction within the scope of the claim may be resorted to without departing from the spirit or sacrificing any of the advantages of the invention.

To more fully comprehend the invention, reference is directed to the accompanying drawings, wherein:

40 Figure 1 is a vertical sectional view of one of the kilns.

Figure 2 is a view in diagrammatic plan of an arrangement of four kilns successively communicating and discharging into a common stack.

Figure 3 is a view in detail of the cellular kiln floor taken on line 3-3 of Figure 4.

Figure 4 is a sectional view taken on line 4-4 of Figure 3, and

50 Figure 5 is a plan view of the floor top wall,

Figure 6 is a transverse sectional view of the kiln taken on line 6-6 of Figure 1, and

55 Figure 7 is a similar view taken on line 7-7 of Figure 1.

Referring more particularly to the several

views of the drawings wherein like characters of reference designate corresponding parts, the numeral 1 designates a common form of stack about which are arranged one or more kilns 2 of any suitable type, illustrated in Figure 2 as being four in number.

Each of the kilns, which are illustrated as of the "biscuit" type are circular in plan, and comprise the annular side supporting wall 3 connected by an arched dome 4 resting on the upper edge thereof, the wall and dome affording a kiln chamber 5. The wall is provided with a door opening 6, and is formed throughout its periphery with the fire-pots or boxes 7, upwardly from each of which extends a heating flue 8 discharging as at 9 into the kiln chamber adjacent the base of the dome 4, as in Figure 1 of the drawings. The wall 3 below said fire-pots or boxes 7 is formed with an annular duct 10 upwardly from which at spaced intervals, preferably at points between the flues 8, extend exhaust heat flues 11 discharging as at 12 into the kiln chamber 5 at a point 70 slightly above the plane of the openings 9. The annular duct 10 is provided with an inlet opening 13, the use of which is herein-after more fully described.

Within each flue 11 is mounted a suitable damper 14, which dampers are capable of independent operation whereby the heat admitted into the kiln chamber 5 through the flues 11 may be directed to enter the chamber at any suitable point or points. The dome 4 is preferably provided with the well known cooling flues 15.

Each kiln is provided with a cellular floor construction 15' consisting of the top wall 16 formed of any suitable type of apertured members 17 resting on the ported parallel spaced feather walls 18 which in turn are supported on a suitable ported wall 19 resting on the side walls 20 of the outlet channels 21 within the base of the kiln. The channels in plan radiate from a common central point, and at their point of radiation communicate with the elbow portion 22 of a stack flue 23 connecting directly with the stack, and each having a damper 24 therein. A branch flue 25 leads from the stack flue 23 and connects with a succeeding kiln 2 through the inlet opening 13, and within which branch flue is mounted a suitable damper 26. This arrangement of connecting each kiln directly with the stack through a damper controlled flue 23, and with an ad-

ja⁵cent kiln through a damper controlled branch flue 25 enables the heat from the fire-pots of any kiln to pass from the kiln chamber 5 through the flue 23 to the stack, or if it is desired the same can be conducted through the branch flue into a succeeding kiln, where it enters through flues 11 into the chamber 5 of said kiln, and then, if desired, may be conducted to the stack or into another kiln, 10 this being accomplished by the operation of the dampers 24 and 26.

It will be apparent that the present arrangement enables the utilization of the heat from one kiln in another, or in a series of 15 kilns before the same is conveyed to the stack, thereby enabling the heat from one kiln in operation to be conducted to any kiln to dry the contents thereof, thus reducing the cost of firing, and enabling the manufacture of 20 articles at a materially lower cost than when a single kiln discharging directly into the stack is employed.

It will be observed in my present construction that the fire box flues are formed within 25 the wall affording a continuous unbroken smooth inner surface for the kiln chamber

thereby providing a greater firing space for the material to be fired over kiln constructions now commonly in use employing what are commonly termed bags projecting into 30 the kiln and which provide the flues for the fire boxes.

Having thus described my invention, what I claim as new and desire to secure by Letters Patent of the United States is:—

A cylindrical kiln comprising a main wall having a smooth inner surface, a dome supported thereby, said main wall provided interiorly with a plurality of vertical flues each communicating at its upper end with the interior of the kiln, said wall being formed interiorly of its base with an annular duct with which the lower ends of alternate flues connect, said wall being further provided interiorly with a plurality of fire-pots opening at the exterior of the wall and one associated with alternate flues, and an outlet beneath said kiln connecting with said duct.

In testimony whereof I have signed my name to this specification.

ROBERT J. DYER.
